UNITED STATES PATENT OFFICE.

AARON J. TORRISON, OF MANITOWOC, WISCONSIN.

FORM FOR DISPLAYING CLOTHING.

1,203,815.

Specification of Letters Patent.

Patented Nov. 7, 1916.

Application filed July 20, 1915. Serial No. 40,989.

To all whom it may concern:

Be it known that I, AARON J. TORRISON, a citizen of the United States, residing at Manitowoc, in the county of Manitowoc and State of Wisconsin, have invented a new and useful Form for Displaying Clothing, of which the following is a specification.

This invention relates to an improvement in forms for displaying clothing.

10 The object is to mount a frame on the top of a counter or show case upon which garments may be hung for the purpose of displaying the same.

15 A further object is in the provision of means for maintaining the frame in an upright position upon the counter or show-case, and which will permit the frame to be swung to practically a horizontal position, so that the garments can be removed from 20 the frame, examined, and displayed to customers from the floor, and when it is desired to return the frame to its normal position upon the counter or show-case, the said means will automatically return the frame 25 to its upright position on the counter or case.

With a device of this character it is possible to conserve floor space and yet the garments are always accessible and examinable from the floor of the room. Furthermore, 30 garments supported or hung on a frame are easy to examine, and the clerks are saved the trouble of checking over or pulling out various garments for the inspection of a prospective purchaser.

35 The invention consists of certain novel features of construction and combinations of parts which will be hereinafter described and pointed out in the claims.

It will be evident that many slight 40 changes may be made in the form and arrangement of the several parts to be described without departing from the spirit and scope of the invention, and hence I do not wish to be limited to the exact construction herein set forth.

In the accompanying drawings,—Figure 1 is a perspective view showing the invention applied to a show-case or counter, and indicating by dotted lines the position assumed 50 by the frame when it is desired to inspect the garments. Fig. 2 is a view in front elevation of the weight casing. Fig. 3 is a longitudinal vertical sectional view of the weight casing. Fig. 4 is a horizontal sectional view of the weight casing on the line 4—4, of Fig. 2. Fig. 5 is a horizontal sec-

tional view on the line 5—5 of Fig. 2. Fig. 6 is a horizontal sectional view on the line 6—6 of Fig. 2. Fig. 7 is a horizontal sectional view on the line 7—7 of Fig. 2. Fig. 8 is a detail view partly in section showing the manner of mounting the frame upon the counter or show-case.

A represents the wall of a room, and B is a show-case or counter, which is mounted 35 upon the floor 1 and preferably located along the wall A.

Mounted along the wall A and extending through the top and rear side of the show case is a vertical weight casing. The casing 70 consists of a front 2, back 3 and sides 4. Doors 5—5 are located at the front of the casing, and are hinged to one of the sides 4 by means of hinges 6, the sides 4 being provided on their inner surfaces with a plurality of grooves. The grooves 7—7 on each side extend from the upper ends of the sides downwardly nearly to the bottom of the sides, or practically three-fourths of the length of the sides. Grooves 8 extend downwardly from the upper end of each side to about midway of the length of the sides, and grooves 9 of each side extend downwardly from the upper end for about one fourth of the length of the sides. While I have specified in a general way the length of these grooves, it is not the intention to limit myself to any specific length of grooves as conditions may require a greater number of grooves or grooves of greater length. 90

Mounted in the casing are a plurality of weights C, D, E and F. Each weight is composed of a plurality of lifts or sections, the number of lifts or sections employed being governed by the object or frame to be 95 elevated and sustained in an upright position. The weights C, D and E are all provided with a plurality of tongues. The weight C is provided with five tongues 10—10 on two sides thereof, the tongues 10 being suitably spaced apart and adapted to travel in the grooves 7, 8 and 9 in the sides of the weight casing. The grooves 9 are provided with shoulders 11 at their lower terminals for forming seats or stops for the 105 uppermost weight C, thereby preventing the weight C from traveling downwardly in the weight casing more than one-fourth of the distance. The weight D is provided with four tongues 12, which are adapted to travel 110 in grooves 7 and 8. The grooves 8 are provided with shoulders 13 for limiting the

downward movement of the weights E. The weight E is provided with two tongues 14 on each side thereof, which are adapted to travel in the grooves 7 of the weights 4, 5 and the grooves 7 are provided with shoulders 15 at their lower ends for limiting the downward movement of the weights E. The weight F is free to travel the entire length of the weight casing as it does not have interlocking engagement with the sides of the 10 weight casing.

The several weights C, D, E and F are provided with holes or openings 16 which are formed centrally therethrough, and radial slots 17 are formed in the several lifts leading to the vertical slots 16. A rope or cable 18 is inserted through the slots and into the openings 16 of the several weights, and is fastened at its lower terminal to a 20 plate 19 which is received in a recess 20 formed in the lower surface of the lowermost weight F. The rope or cable 18 passes through an opening formed in the top or cover 21 of the casing, and over a pulley 22 which is mounted in arms 23 on a bracket 24. The bracket 24 is preferably fastened to the back 3 of the casing which projects above the top or cover 21.

Mounted upon the top of the show-case 30 or counter B are brackets 25, which are provided with hollow curved arms 26, the upper terminals of the arms extending laterally in a horizontal plane. The ends of the arms on the brackets extend toward 35 each other. Vertical bars or uprights 27 are provided with outwardly extending terminals 28 at their lower ends, which are adapted to enter the hollow arms 26 for forming a pivotal connection between the uprights 40 and brackets. Other means of pivoting the bars or uprights would answer as well. The upper terminals of the uprights extend outwardly, or at right angles, and connected thereto is a transverse or cross-bar 29. A 45 collar 30 is mounted on the bar 29 and extending obliquely and upwardly therefrom is a projection 31 to which the upper end of the cable 18 is connected. Extending from the projection 31 to the upper terminals 50 of the uprights 27 is a guy rod 32. A rod 33 is connected to the lower terminals of the uprights 27, for affording rigidity to the uprights, and the uprights 27, the bar 29 and the rod 33 form a display frame for 55 supporting garments, which may be supported upon the bar 29 by means of garment hangers and the like, as indicated in dotted lines in Fig. 1.

A chain 34 is connected to the collar 30, 60 and extends downwardly to the counter or show-case where it is accessible for the purpose of pulling or drawing the display frame downwardly so that the garments will be swung to an elevation where they can be 65 removed from the bar 29 for inspection.

The uprights 27 may be drawn downwardly so that they will rest upon the upper surface or top of the show case, or counter B, and the bar 29 will project below the upper surface of the counter or show case. When the display frame is in this position it is possible for a clerk to remove or apply garments to the bar 29 without the necessity of using a ladder or mounting the show-case or counter to remove or hang garments on 75 the bar 29.

When it is desired to lower the frame the chain 34 is grasped and the bar 29 and uprights 27 are drawn downwardly to their lowermost positions. This downward movement of the bar 29 and uprights 27 causes the weight F to be moved upwardly in the weight casing and as it travels upwardly it collects the various weights, the weight E being the first to be engaged and carried 80 by the weight F. Then the weight B is engaged and carried, and finally the weight C. Of course, if it is necessary to lower the frame to its lowermost position all of the weights will be collected and carried vertically through the casing, the number of weights which are picked up by the weight F depending entirely on the elevation to 85 which the weight F travels.

When it is desired to return the frame to 90 its upright position, the bar 29 is given a slight push in an upward direction, which starts or causes the weights to travel downwardly in the weight casing. The weights when started are caused to move downwardly in the weight casing and will continue to draw or pull the frame to an upright position upon the counter or show-case. During the downward travel of the several weights, the weights C, D and E will 95 stop when the tongues formed thereon come in contact with the shoulders which form the supports for the weights in the casing. The weight F, however, will continue to travel until it reaches the bottom of the 100 weight casing. When the weight F has reached its limit of movement the display frame has been brought to its proper position and it will be maintained in such 105 position by the weight F until the chain 34 is pulled downwardly for drawing the frame to 110 its lowermost position.

From the foregoing it will be seen that as 115 the lower weight F collects the intermediate weights D and E, and the upper weight C on its upward travel through the weight casing, the display frame will be retarded in its downward movement. In other words, the weights will act as a check upon the movement of the frame. The collecting of 120 the weights in this manner makes it possible to operate and lower the display frame much easier, because it is not necessary to exert a pull upon the frame at the beginning 125 sufficient to raise all the weights even- 130

tually carried by the lowermost weight. The collecting of the weights at various intervals, during the travel of the display frame in a downward direction, by the 5 lowermost weight does not add any perceptible load but gradually checks and counteracts the fall of the display frame.

When the weight F is returned to its lowermost position, upon the upward movement of the display frame to its normal position, the weights C, D and E will automatically become disengaged therefrom as they come in contact with the shoulders formed in the casing for supporting the 15 weights.

What is claimed is:

1. The combination with a show case or counter, of a display frame comprising relatively long spaced bars or uprights and a 20 connecting transverse bar, means on top of the show case or counter spaced a relatively short distance inwardly of the lateral edge thereof for pivotally mounting the ends of the bars or uprights to the show case or 25 counter, means for maintaining the display frame in an upright position above the show case or counter so that garments hung from the transverse bar will be held in an elevated position, said means permitting the 30 display frame to be swung down to a horizontal position, thereby causing the transverse bar to project beyond one side of the counter or show case.

2. The combination with a show case or 35 counter, of a display frame comprising spaced bars, the upper terminals of the bars being curved and extending forwardly, and a transverse bar connecting said curved ends causing the transverse bar to project below 40 the plane of the top of the show case or counter when the display frame is in its lowered position, means for pivotally connecting the lower ends of the bars or uprights to the show case or counter, means 45 for maintaining the display frame in an upright position above the show case or counter, so that garments hung from the transverse bar will be held in an elevated position, said means permitting the display 50 frame to be swung down in a horizontal position.

3. The combination with a show case or counter, of a pair of uprights pivoted on the counter and adapted to project upwardly 55 above the same and being of a length to project laterally therebeyond when swung downwardly into a horizontal position, a transverse bar joining the upper ends of the uprights, and being offset forwardly from the plane thereof whereby 60 upon the downward swinging of the uprights the transverse bar is disposed lat-

erally beyond the edge and below the plane of the top of the show case or counter.

4. The combination with a counter or 65 show case, of spaced apart brackets mounted on the top of the counter or show case, uprights pivoted at their lower ends upon the brackets, and having outwardly curved upper ends, a cross bar joining the outer extremities of said curved ends, and adapted to receive the goods to be displayed, a collar rotatably mounted on the cross bar, a cable secured at one end to the projections, a pulley disposed above and rearwardly of 70 the sleeve, and over which the cable is supported, and a weight on the opposite end of the cable to counter-balance the weight of the cross bar and the goods carried thereby.

5. The combination with a show case or 80 counter, of a pair of uprights pivoted in longitudinally spaced apart relation upon the top of the counter, a cross bar joining the upper ends of the uprights to receive goods to be placed on display, means for 85 maintaining the uprights in vertical position to support the goods high above the show case or counter, the pivotal connections between the uprights and the show case or counter being each spaced inwardly an equal 90 distance from the lateral edge of the counter, and the standards being of a greater length than said distance, whereby upon the downward swinging of the uprights said cross bar is caused to project beyond the lateral 95 edge of the counter or show case and substantially in parallelism therewith.

6. The combination with a pivotally mounted display frame, of a weight casing, said casing having grooves formed in the 100 sides thereof of various lengths, a plurality of weights mounted in the casing having tongues thereon adapted to enter the grooves of the casing for guiding the weights in their movement, shoulders formed at the 105 lower terminals of the grooves for supporting the weights at various elevations in the weight casing, a cable or rope connected to the display frame extending into the weight casing, and a weight connected to the rope 110 or cable for maintaining the display frame in an upright position, said weight having free movement lengthwise of the casing and adapted to collect the various weights in the lowering of the display frame for retarding 115 the downward movement of the display frame.

In testimony that I claim the foregoing as my own, I have hereto affixed my signature in the presence of two witnesses.

AARON J. TORRISON.
